United States Patent Office

Des. 189,233
Patented Nov. 15, 1960

189,233

HOOD

Charles N. Gardner, Suitland, Md., and Joseph De Grazia,
Washington, D.C., assignors to the United States of America as represented by the Secretary of the Army

Filed Apr. 12, 1960, Ser. No. 60,194

Term of patent 14 years

(Cl. D3—13)

(Granted under Title 35, U.S. Code (1952), sec. 266)

The invention described herein may be manufactured and used by or for the Government for governmental purposes, without the payment to us of any royalty thereon.

We claim:

The ornamental design for a hood, substantially as shown.
